UNITED STATES PATENT OFFICE.

CHARLES K. WOODBRIDGE, OF NEW YORK, N. Y., ASSIGNEE TO DICTAPHONE CORPORATION, OF BRIDGEPORT, CONNECTICUT, A CORPORATION OF NEW YORK.

SOUND COLLECTING AND TRANSMITTING.

Application filed May 29, 1924. Serial No. 716,626.

This invention relates to sound-collecting and transmitting means and in the embodiment shown as illustrative of the invention, it is particularly adapted for use with dictating machines.

In the accompanying drawings, which show by way of example several embodiments of this invention,

Figure 1 is a side elevation, partly in section, of one form of sound-collector made in accordance with the present invention, showing a relative large horn-shaped sound-collecting portion, and means for allowing swiveling movement of same on the handle.

Fig. 2 is a sectional detail view showing on an enlarged scale the connection between the sound-collecting portion and the handle.

Fig. 3 is a sectional view of the mouthpiece showing means for securing it to the body portion of the sound-collector.

Fig. 4 is a side view, partly in section, of a modification of the device shown in Fig. 1, the mouthpiece and body portion of the sound-collector being merged into one piece and different means for securing the sound-collector to the handle being shown.

Fig. 5 is a view similar to Figs. 1 and 4 of another modification of the present invention, the body of the sound-collector having provision for pivotal movement in addition to provision for swiveling movement.

As in the usual form of device now used upon dictating machines to collect and transmit sound from the dictator to the recording mechanism, the speaking-tube 10 is connected in any suitable manner to a handle 11, having a hook-shape guard 12 which engages a part of the dictator's hand, while the handle 11 is being held, and which assists the dictator in holding the handle. And, opposite the guard 12 on the handle 11, there is provided a button 13 which is used to control the operation of the machine from the handle 11.

In sound-collectors heretofore provided for use in dictating machines, the mouthpiece was connected to the handle portion by a tube which was bent so that, when held substantially vertical in front of the dictator, the mouthpiece would extend at an angle from the handle in the direction of the dictator's mouth. When held in this position, the control button 13 was directly in front of the operator, while the guard 12 was at the opposite side of the handle, a

position which it was necessary to maintain due to the angular position of the mouthpiece with relation to the handle. In certain sound-collectors heretofore used there was very little concentration of sound energy, because of the fact that the mouthpiece was small with relation to the diameter of the conveying tube.

In another known form of sound-collectors, the mouthpiece and handle constituted a relatively long horn which was made exceptionally wide at its receiving end and gradually tapered down through the handle to the dimension of the speaking-tube proper.

This construction produced a large space between the lip of the mouthpiece and the speaking-tube proper, the column of air of which was set into vibration and acted as a resonator for the sound passing through the horn.

The resonating action of such sound-collectors produced what is termed a "tubby" effect, such as is particularly noticeable in connection with megaphones. Further, the horn-chamber produced had the effect of lowering the fundamental vibratory characteristics of the recording diaphragm which, consequently, had a tendency to blast under the influence of the higher pitch sounds.

The disadvantages of both types of sound-collectors, above referred to, so far as they relate to the quality and volume of the sound collected and transmitted, are overcome by the present invention, the one by making the receiving end of the device larger so that more of the sound is collected, and the other, by making the sound-collector so that its sound-passage is relatively short and rapidly decreasing in cross-sectional area from the mouthpiece to the handle 11. This idea is embodied in the sound-collectors shown in Figs. 1 and 4.

In the form shown in Fig. 1, the handle 11 has connected to it a horn-shaped tube, hereinafter called the horn 14, between it and the mouthpiece 15, which rapidly decreases in cross-sectional area as it approaches the handle 11. The mouthpiece 15 flares outwardly from its point of connection to the horn 14 so as to present a relatively large opening and collect a substantial portion of the sound emitted by the dictator.

Since the total axial length of the mouthpiece 15 and the horn 14 is equal to only about twice the diameter of the mouthpiece 110

at its lip 16, producing a sound-collector which is relatively short in proportion to the diameter of its receiving end, there is no extensive chamber to act as a resonator of the incoming sound and change its natural characteristics.

In the form of device shown in Fig. 4, the mouthpiece 15^a has a horn part 14^a formed integral with it to avoid obstructive overlapping joints and to reduce the initial production costs. Since the part is usually made of glass, however, it is more liable to breakage than the device shown in Fig. 1 in which the mouthpiece 15 alone is made of glass. As shown in Fig. 4 the mouthpiece lip 16^a has substantially the same diameter as the lip 16 shown in Fig. 1, but the axial length from the lip to the handle 11^a is about equal to the diameter of the mouthpiece across the lip 16^a. In this case the sound-collector is shorter so that any tendency of the column of air in the mouthpiece to resonate is reduced to a minimum, while the efficiency of the sound-collector is still relatively high.

In addition to providing the novel and advantageous shapes of sound-collectors above referred to, the present invention provides means whereby the sound-receiving part of the collector may be adjusted to suit the convenience of the dictator. This is a very desirable and advantageous feature since it permits the angularly disposed lip of the mouthpiece to be shifted so as to be directly in front of the dictator when the handle with its guard 14^a and control button 13 is held in a position most convenient to the dictator.

In the form shown in Fig. 1, the sound-collector is mounted to swivel on the handle 11 so that the lip 16 of the mouthpiece 15 may be moved by rotating the horn 14 about the axis of the handle 11. The horn 14 is provided with a neck 17 which preferably telescopes with the end 18 of the handle 11, and it is about this end 18 that the horn 14 may be rotated. To hold the neck 17 of the horn to the end 18 of the handle against accidental separation and yet allow free rotation of the horn 14 upon the handle 11, a self-locking detent is provided between the two parts. This is preferably in the form of a split spring-ring 19 (see Fig. 3), which fits within a circumferential groove 20 provided in the end 18 and a similar groove 21 provided in the neck 17, the arrangement being such that the spring-ring 19 normally assumes a position where it simultaneously engages both grooves. In assembling the device, the spring-ring 19 is placed within the groove 20 and then the end 18 is slid into the neck 17. At the time the end 18 engages a shoulder 22 provided on the neck 17, the spring-ring is opposite groove 21 and because of its resiliency,

springs outwardly into the position shown in Fig. 3. In this position, the spring-ring engages the wall 23 of the groove 20 and an abrupt cam-surface 24 of the groove 21 and thus holds the parts against separating movements. To withdraw the end 18 from the neck 17, it is necessary to cam the spring-ring 19 back into the groove 20, and to do so, a great deal of force is needed because of the abruptness of the cam surface 24 which produces much friction between it and the spring, and the latter and the abrupt surface 23 of the groove 20. Thus, the end 18 is held in the neck 17 against accidental displacement.

In order to secure the sound-collector in its adjusted position against accidental or undesired rotation upon the handle 11, there is provided a clamping nut 25 threaded in the neck 17 and engaging the end 18. When it is desired to change the position of the sound-collector, the screw 25 is released and the collector is rotated about the tube.

In the form shown in Fig. 4, the mouthpiece 15^a including the horn-portion 14^a is mounted for turning movement on the handle to be adjusted to a convenient position for the dictator, and for this purpose, the mouthpiece is provided with a bead 26 adapted to frictionally engage a socket 27 on the handle 11^a and comprising a plurality of resilient tongues 28 adapted to engage over the bead. The socket 27 has a neck 29 fixed in the handle 11^a. With this form of device, it is merely necessary to rotate the mouthpiece in its socket 27 to the desired position, the friction between the tongues 28 and the bead 26 being sufficient to hold the mouthpiece in adjusted position.

In Fig. 5, there is shown a modification of the present invention. In this form the mouthpiece is not only capable of swiveling movements upon the handle to adjust it angularly about the axis of the handle with relation to the guard 12 and the button 13, but is also capable of pivotal movement to change its angular position with relation to the axis of the handle.

For the former purpose, the mouthpiece is supported by a tube 30 which is adapted to telescope over the end 18^b of the handle 11^b, which is provided with a hollow bead 31 adapted to receive the round-head of a screw 32 threaded in the end 18^b of the handle. The screw 32 acts as a key to hold the end 18^b and the tube 30 together. In assembling this device, the screw 32 is passed through an opening 33 in the hollow bead 31 and is fastened in place in the end 18^b. The clearance between the head of the screw 32 and the walls of the groove 31 is sufficient to allow free rotation of the tube while the screw-head prevents the tube 30 from being drawn off the end 18^b.

For the purpose of allowing the mouth-

piece 15^b to be adjusted angularly with relation to the axis of the handle 11^b, a tube 34 which carries the mouthpiece, is pivotally mounted on a rod 35 carried by the tube 30 at right angles to the axis of the handle 11^b.

The tube 34 has arcuate portions 36 adapted to extend inside of and contact with a curved apron 37 carried by the tube 30, so that in all positions of the tube 34, the sound-¹⁰ passage will be maintained closed by the arcuate portion 36 and the apron 37.

The mouthpiece 15^b is provided with a bead 38 engaging a plurality of resilient tongues 39 integrally connected together and secured in a socket 40 forming part of the tube 34. In applying the mouthpiece to the tube 34, the bead 38 is forced under the tongues 39 and is yieldingly held by the tongues against accidental displacement.

While in the forms shown in Figs. 4 and 5, the mouthpieces 15^a and 15^b are resiliently held in place by spring means, it is usually preferable that the mouthpiece be more securely attached to the other parts. One advantageous form of such connection is shown in Figs. 1 and 2 in which the glass mouthpiece 15 is positively held in position on the horn 14 by a cylindrical clamping-ring 41. The mouthpiece 15 engages the end 42 of the horn 14 while the cylindrical clamping member 41, which is threaded in the mouthpiece, has a flange 43 engaging a shoulder 44 on the mouthpiece. When the clamp 41 is screwed into the end of the horn 14, it securely holds the mouthpiece in the position shown in Fig. 1.

For the purpose of facilitating the adjustment of the clamping-ring 41, it is provided with notches 45 adapted to be engaged by lugs 46 provided on the mouthpiece. In applying the mouthpiece 15 to the horn 14, the clamp 41 is first dropped into the mouthpiece 15 so that its notches 45 are engaged by the lugs 46 of the mouthpiece, and then the latter is rotated until the end of the clamp 41 is screwed tightly in place on the horn 14.

Variations and modifications may be made within the scope of this invention, and portions of the improvements may be used without others.

While all of the embodiments of the present invention shown herein are covered generically by the appended claims, the species claims for the embodiments of the invention shown in Figs. 4 and 5 are not contained in this application, but are presented respectively in my co-pending application, S. N. 150,578, filed November 24, 1926, and S. N. 185,570, filed April 21, 1927, both divisions of this application.

Having now described the invention, what is claimed as new and for which it is desired to obtain Letters Patent, is:

1. A sound-receiving device comprising a

handle portion and an outwardly flaring mouthpiece portion, and means for adjustably connecting the handle portion and the mouthpiece portion to allow rotary movement of one relative to the other.

2. A sound-receiving device comprising a handle portion; a sound-receiving portion flaring outwardly from the handle portion and connected to the handle portion, and adapted to be angularly adjusted with relation thereto; and a mouthpiece portion detachably connected to the outwardly flaring sound-receiving portion and coextensive therewith.

3. In combination, a hand-held sound-conveyor; a sound-collector having its mouth disposed in a plane at an angle to the plane of the axis in which the sound-conveyor lies when connected to the latter; a swivel connection between the sound-conveyor and the sound-collector; and means for holding said sound-conveyor and sound-collector against relative movement about said swivel connection.

4. In combination, a hand-held sound-conveyor; a mouthpiece; a horn-shaped part between the mouthpiece and the sound-conveyor; means for connecting the mouthpiece to the horn-shaped part; and a self locking connection for connecting the horn-shaped part to the sound-conveyor.

5. In combination, a hand-held sound-conveyor; a curved sound-collector; and means for interconnecting the sound-collector and the sound-conveyor, said means allowing rotation of the one part relative to the other and preventing longitudinal movement of the one part relative to the other.

6. In combination, a cylindrical, hand-held, sound-conveyor; an outwardly flaring horn detachably connected to the sound-conveyor; and a flaring mouthpiece detachably connected to the flaring horn.

7. In combination, a hand-held sound-conveyor; a sound-collector, said sound-collector and sound-conveyor having an overlapping connection with each other and each having circumferential grooves substantially aligned with each other, when in predetermined overlapped condition, and yieldable means adapted to simultaneously engage both grooves to removably hold the sound-collector and the sound-conveyor together.

8. In combination, a pair of sound-passages having a telescoping connection with each other at their adjacent ends and having cooperating circumferential grooves which are substantially aligned when the two parts are in predetermined positions; and yieldable means adapted to simultaneously engage both grooves to removably hold the parts together.

9. In combination, a pair of sound-passages having a telescoping connection at their adjacent ends; and means entirely

concealed within the telescoping connection, for rotatably holding the two parts together.

10. In combination, a pair of sound-passages having a telescoping connection with each other at their adjacent ends, and having on the contacting walls of the telescoping connection, aligning grooves; and yieldable means adapted to simultaneously engage said grooves to hold the parts removably connected together.

11. In combination, a sound-conveyor having a substantially uniform diameter throughout its length; a sound-collecting horn removably attached to the receiving end of the conveyor; and a mouthpiece removably attached to the horn, the horn and mouthpiece being tapered and having co-extensive internal surfaces.

12. In combination, a hand-held sound-conveyor; a sound-collector having its mouth disposed in a plane at an angle to the plane of the axis of the sound-conveyor; hand-engaging parts on the hand-held sound-conveyor; and a swivel connection between the sound-conveyor and the sound-collector whereby adjustment of the angularly disposed mouth of the sound-collector may be effected relative to the hand-engaging parts on the sound-conveyor and about the axis of the latter.

13. A sound-receiving device comprising a handle portion; a mouthpiece portion; means for adjustably connecting the handle portion and the mouthpiece portion to allow

movement of the one relative to the other; and means for holding said mouthpiece portion against unintentional movement.

14. A sound-receiving device comprising a handle portion; a mouthpiece portion; means for adjustably connecting the handle portion and the mouthpiece portion to allow movement of the one relative to the other; and means for positively locking said mouthpiece portion against movement relative to said handle portion.

15. A sound-receiving device comprising a tubular handle portion; a tubular mouthpiece portion telescoping with the handle portion; and a set-screw in one of said portions and engaging the other of said portion to prevent movement of the one portion relative to the other portion.

16. In combination, a hand-held sound-conveyor; a sound-collector having its mouth disposed in a plane at an angle to the plane of the axis in which the sound-conveyor lies; manually operable means on the hand-held sound-conveyor; and a swivel connection between the sound-conveyor and the sound-collector whereby adjustment of the angularly disposed mouth of the sound-collector may be effected relative to the manually operable means on the sound-conveyor and about the axis of the latter.

Signed at Bridgeport, in the county of Fairfield, and State of Connecticut, this 26th day of May, 1924.

CHARLES K. WOODBRIDGE.
